[57] CLAIM

The ornamental design for a bar code wedge reader, as shown and described.

DESCRIPTION

FIG. 1 is a front perspective view of a bar code wedge reader according to our new design, showing the front, top and left sides thereof;

FIG. 2 is a left side elevational view thereof;

FIG. 3 is a right side elevational view thereof;

FIG. 4 is a rear elevational view thereof;

FIG. 5 is a rear elevational view of a second embodiment thereof, the undisclosed views being identical in appearance to those of the first embodiment; and,

FIG. 6 is a bottom plan view thereof.

FIG. 2

FIG. 3

FIG. 5

FIG. 6

FIG. 6

FIG. 4
